P. DIEHL & M. HEMLEB.
SEWING MACHINE PULL-OFF.
APPLICATION FILED NOV. 18, 1912.

Patented Aug. 4, 1914

UNITED STATES PATENT OFFICE.

PHILIP DIEHL AND MARTIN HEMLEB, OF ELIZABETH, NEW JERSEY, ASSIGNEES TO
THE SINGER MANUFACTURING COMPANY, A CORPORATION OF NEW JERSEY.

SEWING-MACHINE PULL-OFF.

1,105,968.

Specification of Letters Patent.

Patented Aug. 4, 1914.

Application filed November 18, 1912. Serial No. 731,922.

To all whom it may concern:

Be it known that we, PHILIP DIEHL and MARTIN HEMLEB, citizens of the United States, residing at Elizabeth, in the county of Union and State of New Jersey, have invented certain new and useful Improvements in Sewing-Machine Pull-Offs, of which the following is a specification, reference being had therein to the accompanying drawings.

10 While applicable to different classes of sewing machines employing a rotary loop-taker carrying a lower thread, the present improvement is designed chiefly for embodiment in that class of lock-stitch loop-takers having a plurality of rotations imparted thereto for each reciprocation of the needle. It has been customary heretofore to provide such a loop-taker with a pull-off flange acting to draw thread from the bobbin-case for 20 each stitch; but with a plural-rotation loop-taker so fitted, the lower thread is repeatedly engaged by the pull-off element in each stitch-forming cycle, thereby disturbing the previously set stitch and impairing the effectiveness and appearance of the seam.

25 The present invention therefore has for its primary object to provide the described class of rotary loop-taker machines with simple and effective means for properly drawing off the lower thread for each stitch without affecting the previously formed and set stitch.

In the preferred embodiment of the invention, the non-rotary thread-case is journaled in the loop-taker and has a thread-guiding arm or projection over which the lower thread is led to the work, and the feed-dog is provided with a pull-off rib or flange movable vertically between the 35 thread-guiding arm of the thread-case and the needle-path which determines the position of the needle-hole of the throat-plate through which the lower thread passes to the work in the stitching operation. By this 40 means, the loop-taker is entirely relieved of its lower thread drawing function, thus avoiding the dislodgment of the previous stitch in a succeeding stitch-forming cycle, and the feed-dog, which makes only a single 45 excursion for each stitch, is caused to draw off the lower thread for a succeeding stitch just at the time when the needle is descending and when its eye is below the work and the portion of the needle-thread leading 50 therfrom to the previous stitch is nipped

in the goods and held taut so as to resist the strain upon the lower thread imposed by the pull-off.

In the accompanying drawings, Figure 1 is an elevation, with the frame in section, 60 of a Singer rotary hook machine similar to that represented in the application Serial No. 728,779, filed October 31, 1912, and Fig. 2 an end view of the parts below the bed-plate which latter is represented in 65 transverse section. Fig. 3 is a perspective view representing the member of the thread-case formed with the thread-guiding arm, a portion of the throat-plate and the feed-dog with its pull-off element acting upon 70 the lower thread. Figs. 4 and 5 are sectional elevations of the parts represented in Fig. 3, with both members of the thread-case, and showing the feed-dog in its extreme upper and lower positions. Fig. 6 is a perspective view of the thread-case member 75 provided with the thread-guiding arm, and Fig. 7 a perspective view, taken from the lower side, of the feed-dog provided with the pull-off rib or flange.

As represented in the drawings, the frame of the machine is constructed with the bed-plate 1, hollow standard 2 and tubular arm 3 in which is journaled the main-shaft 4 carrying at its rearward end the balance-wheel 5 and at its forward end the crank-plate 6 provided with the crank-pin 7 connected by means of the pitman 8 with the collar 9 fixed upon the needle-bar 10, which is provided with the needle 11. Upon the 80 rearward portion of the main-shaft is fixed the bevel-gear 12 meshing with a bevel pinion 13 upon the upper end of a vertical shaft 14 having upon its lower end the bevel pinion 15 meshing with a similar pinion 16 upon the loop-taker shaft 17 suitably journaled beneath the bed-plate. The gear 12 is twice the diameter of the pinion 13, and therefore imparts to the vertical shaft 14, and through it to the loop-taker 100 shaft 17, two rotations for each rotation of the main-shaft, and hence for each reciprocation of the needle.

Fixed upon the forward extremity of the shaft 17 is the hub 18 of the loop-taker 19 in 105 the form of a cup-shaped hook provided with a central thread-cavity 20 and with a loop-seizing beak 21 and with spaced and overlying loop-deflector spur 22, as shown and described more fully in the pending ap- 110

lication Serial No. 638,059, filed July 12, 1911. The thread-cavity is provided with the usual annular groove in which is journaled the peripheral bearing rib 23 of the body portion or carrier 24 of the thread-case, which is formed with the central pin 25 and with the forwardly projecting tongue or extension 26 containing the needle clearance aperture 27 and provided with the outwardly extending thread-guiding flange or lip 28 which is shown in the drawings formed with the thread-leading groove or notch 29. The thread-case cap or cover 30 is provided, as represented in the said application Ser. No. 638,059, with the tension spring 31 secured in position by means of the fastening screw 32, and is provided with a tubular post fitted upon the pin 25 and adapted to receive the lower thread bobbin. The cap member 30 is provided with a latch device 33 having a latch element adapted to engage the notched outer end of the pin 25 for locking such member in place.

The notch 29 of the guide-member 28 is entered by a lateral lug 34 of a holding arm 35 secured upon the bottom of the bed-plate 1, so as to restrain the carrier member 24 of the thread-case from turning with the hook, while the cap-member has the usual interlocking connection with the latter whereby it is maintained stationary in the operation of the machine.

The main-shaft 4 has the usual feed-actuating eccentric 36 and feed-lift eccentric 37, upon the former of which is fitted a collar 38 embraced by the fork 39 at the upper end of the link-bar 40. The link-bar has the usual pivotal connection at 40' with a swinging supporting link whose fulcrum is laterally adjustable to vary the resultant vertical movement of the link-bar, as is common to many sewing machines of the Singer type. At its lower end the link-bar is pivotally connected by means of the stud-pin 41 with the lateral arm 42 of the feed rock-shaft 43 journaled beneath the bed-plate and provided with upright arms 44 affording a yoke in which is journaled upon the pins 45 the cross member 46 at one end of the feed-bar 47. The opposite end of the feed-bar is formed with a fork 48 adapted to embrace the roller-stud 49 carried by the lateral arm 50 of the feed rock-shaft 51 having at its rearward end the lateral arm 52 pivotally connected to the lower end of the pitman-rod 53 whose upper end is provided with the strap 54 embracing the feed-lift eccentric 37.

Secured upon the seat 47' of the feed-bar 47 is the shank 56 of the feed-dog provided with the serrated feeding surfaces 57 adapted to move upwardly through the usual apertures 58 of the throat-plate 59, and formed in its lower side with the recess 60 to afford clearance for the loop-taker beak. Depending from the upper wall of the recess

60 intermediate the extreme feeding surfaces 57 of the feed-dog is the pull-off rib or flange 61 which, as represented in the drawings, is disposed in a plane intermediate the guide-arm 28 of the thread-case member 24 and the plane of movement of the loop-taker beak 21 and of the needle.

In threading the machine, the lower thread *s* passes from beneath the tension spring 31 through the delivery eye 30' of the cap-member 30 of the thread-case, and thence upwardly through the usual needle-hole 59' of the throat-plate, as represented in Figs. 2 and 4. The initial stitch or stitches having been formed and set by the action of the take-up arm 62 connected with the needle-actuating crank 7, upon the descent of the needle to present a thread-loop for seizure by the loop-taker beak, the feed-dog effects its descent, carrying with it the pull-off flange 61 which produces a crook in the lower thread *s*, just at the time when the upper thread *n* leading to the previous stitch is taut and securely nipped between the un-grooved side of the needle above the eye and the puncture in the fabric *m*. The bending of the lower thread while its outer end is securely anchored in the fabric by engagement with the taut needle-thread causes the drawing of the succeeding supply through the lower-thread tension so as to properly locate within the body of the material the interlock of the threads in the setting of the stitch formed by the cycle as thus begun.

It is evident that the pull-off member, while preferably formed upon a part of the feed-dog, may be otherwise sustained and actuated, within the scope of the present invention, and that the particular means employed for directing the lower thread from the thread-case and restraining the latter from rotation are not essential.

Having thus set forth the nature of the invention, what we claim herein is:

1. In a sewing machine, the combination with a reciprocating needle, and a rotary loop-taker formed with a thread-cavity and with a loop-seizing beak having a path of movement around an axis transverse to said needle, of a non-rotary thread-case disposed within the thread-cavity of said loop-taker and provided with a thread-guiding member at one side of the needle-path, and a reciprocatory pull-off member having operative rectilinear movements in a path substantially parallel with the needle and intermediate the needle-path and said guide-member.

2. In a sewing machine, the combination with a reciprocating needle, and a rotary loop-taker formed with a thread-cavity and with a loop-seizing beak having a path of movement around an axis transverse to said needle, of a non-rotary thread-case disposed within the thread-cavity of said loop-taker

and provided with a thread-guiding member at one side of the path of movement of the loop-taker beak, and a reciprocatory pull-off member having operative movements in coaction with said thread guiding member in a plane substantially parallel with the path of movement of the loop-taker beak.

3. In a sewing machine, the combination with feeding mechanism comprising a feed-bar with means for imparting thereto lateral and rising-and-falling movements, a reciprocating needle, and a rotary loop-taker formed with a thread-cavity and with a loop-seizing beak having a path of movement around an axis transverse to said needle, of a non-rotary thread-case disposed within the thread-cavity of said loop-taker and provided with a thread-guiding member at one side of the needle-path, and a pull-off member carried by the feed-bar and movable between said guide-member and the needle-path.

4. In a sewing machine, the combination with a reciprocating needle, a loop-taker formed with a thread-cavity and with a loop-seizing beak, and means for imparting to the loop-taker a plurality of rotations for each reciprocation of the needle, of a non-rotary thread-case carrying a lower thread disposed within the thread-cavity of said loop-taker and provided with a thread-guiding arm over which the lower thread is led to the work, and a reciprocatory pull-off member adapted to engage the lower thread intermediate the thread-case arm and the needle.

5. In a sewing machine, the combination

with feeding mechanism comprising a feed-bar with means for imparting thereto lateral and rising-and-falling movements, a reciprocating needle, a loop-taker formed with a thread-cavity and with a loop-seizing beak, and means for imparting to the loop-taker a plurality of rotations for each reciprocation of the needle, of a non-rotary thread-case carrying a lower thread disposed within the thread-cavity of said loop-taker and provided with a thread-guiding arm over which the lower thread is led to the work, and a pull-off member carried by the feed-bar and movable between said guide-member and the needle-path.

6. In a sewing machine, the combination with a reciprocating needle and a rotary loop-taker formed with a thread-cavity and with a loop-seizing beak, of a non-rotary thread-case disposed within the thread-cavity of said loop-taker and formed with a thread-delivery eye, a thread guiding arm carried by said thread-case and formed with a thread-receiving groove in alignment with said delivery eye, a feed-bar, and a pull-off member carried by the feed-bar and movable between said guiding arm and the needle-path.

In testimony whereof, we have signed our names to this specification, in the presence of two subscribing witnesses.

PHILIP DIEHL.
MARTIN HEMLEB.
